UNITED STATES PATENT OFFICE.

CHARLES S. BRANCH, OF HAMMOND, INDIANA.

CIGARETTE-FORMING DEVICE.

1,376,074.

Specification of Letters Patent. Patented Apr. 26, 1921.

Application filed August 9, 1920. Serial No. 402,306.

To all whom it may concern:

Be it known that I, CHARLES S. BRANCH, a citizen of the United States of America, and a resident of Hammond, county of Lake, 5 State of Indiana, have invented certain new and useful Improvements in Cigarette-Forming Devices, of which the following is a specification.

A purpose of this invention is to provide 10 a compact article formed or pressed, from sheet metal, into a shape which is suitable for rolling cigarettes without requiring additional guides or parts riveted or soldered thereto. A further purpose is to provide a 15 cigarette forming device in which duplicate members are hinged together to form the completed article.

An illustrative embodiment of the invention is shown in the accompanying drawings, 20 in which—

Figure 1 is a perspective view of the device.

Fig. 2 is an inside view of one of the two 25 parts of the device.

Fig. 3 is an end view.

Fig. 4 is a transverse sectional view showing the device closed and a cigarette therein.

Fig. 5 is another transverse sectional view 30 but showing the device opened.

The device shown is so designed that it may be made complete by two duplicate parts hinged together, and formed by the same set of dies. The two principal parts 1 and 2 of the device are joined by alternating tongues 3 wrapped around a wire 4, and each part of the body is pressed to form semi-circular receivers 5 and semi-circular ends 6 and upstanding guides 7, all of which are integral. The guides 7 have longitudinal 35 slots 8 through which the cigarette rolling ribbon 9 passes. The guides 7 are spaced outwardly of the abutting edges 10 of the semi-circular ends 6, and therefore provide 40

a longitudinal opening 11 between the guides 7.

In the operation of the device it is first 45 opened on its hinges and tobacco is placed on ribbon 9 between the guides 7, and is pressed downwardly into the pocket formed by the semi-cylindrical portions 5. The device is then closed and the cigarette paper is placed between the guides 7, then by drawing outwardly on one end of the ribbon 9, the tobacco is rolled and the paper is drawn inwardly by contact therewith and with the 50 ribbon around the tobacco and forms the ribbon around the tobacco and forms the cigarette, as is customary with devices of this general class.

Although but one specific embodiment of 55 this invention has been herein shown and described, it will be understood that numerous details of the construction shown may be altered or omitted without departing from the spirit of this invention as defined by the following claims.

I claim:

1. A cigarette forming device having two semi-cylindrical parts which are hinged together along their lower edges, and each of which is provided with integral semi-disks 70 at each end, and an integral upwardly extending guide spaced inwardly from the abutting edges of the semi-disks.

2. A cigarette forming device having two semi-cylindrical parts which are hinged to- 75 gether along their lower edges, and each of which is provided with integral semi-disks at each end, and an integral upwardly ex- 80 tends guide spaced inwardly from the abutting edges of the semi-disks, each of said guides being provided with a longitudi- nal slot near its lower edge.

Signed at Chicago this 6th day of August, 1920.

CHARLES S. BRANCH.
